(57) **CLAIM**

The ornamental design for an annular magnet housing, as shown and described.

DESCRIPTION

FIG. 1 is a top perspective view of an annular magnet housing in an environment in which it may be used;

FIG. 2 is a top perspective view thereof;

FIG. 3 is a bottom perspective view thereof;

FIG. 4 is a top view thereof;

FIG. 5 is a front view thereof, the left side, right side and rear being mirror images thereof; and,

FIG. 6 is a bottom view thereof.

The broken lines depicting a sequestration device having a fluid reservoir connected thereto in FIG. 1 represent environmental structures form no part of the claimed design. The remaining broken lines depict portions of the annular magnet housing that form no part of the claimed design.
